UNITED STATES PATENT OFFICE.

ALWIN SCHMITZ, OF ERFURT, GERMANY.

PRESS FOR PRESSING HOLLOW BRONZE OBJECTS.

Application filed September 8, 1925. Serial No. 55,114.

The present invention relates to a press provided with a matrix for determining the cross sectional dimensions of the material and intended for pressing sockets, bushings and other hollow objects out of bronze of any composition, the said press being characterized by the fact that a countersocket arranged within the matrix and subjected to brake action presses against the material as the material rises in the matrix under the pressure of the punch so as to prevent the material from tearing while at the same time condensing it. The countermember within the matrix is subject to the retardative action of a screw spindle brake. At the moment when the punch actuated by the press spindle acts upon the bronze to be pressed the countermember presses upwardly against a pressure plate resting on it, so that the latter, together with a braking beam suitably connected with it is pushed up. Loosely arranged in the pressure frame, at each side of the brake beam, is a screw spindle, each of which is provided with correspondingly vertical threads, the said screw spindles being adapted to rotate in stationary bearings of the brake beam. When the brake beam is moved upwardly the brake action of the screw spindles in the bearings of this brake beam causes counterpressure to be applied to the work piece to be pressed and this counterpressure continues to be slowly and uniformly applied by the turning movement of the spindles in their bearings so long as the brake beam moves upwardly until the work piece is finished.

The hollow object to be pressed is therefore subjected to uniform and unvarying counterpressure from beginning to the end of the operation on same, so that any tearing or cracking of the work piece is effectively prevented.

Any known form of ejecting device may be arranged on the ram of the press and extend through the bed of the press in known manner for the purpose of ejecting those work pieces that stick to the matrix.

All attempts hitherto made to produce perfect hollow bodies of bronze by means of pressing have been in vain. While pressing has been successfully applied to other metals, such as brass, the production of hollow bodies of bronze has always been thwarted by the peculiarity of the material. When an attempt is made by known

methods to press hollow bodies out of bronze the edges of the bushings etc. to be pressed usually tear and crack, whereas hollow bronze bodies made by a press according to the present invention do not reveal those drawbacks but remain whole and free from cracks; they are even improved in so far as the material is condensed during the pressing process. After being pressed they can be used at once without any finishing work except for a thin bottom which must be ejected by a special press in a simple and known manner. The press of the present invention, therefore, represents an advance in the art.

One form of the invention is illustrated in the accompanying drawing which shows a side view and a partial longitudinal section of the press, Fig. 1 showing the position of the parts before the pressing begins; Fig. 2 showing the position of the parts when the pressure ceases, and Fig. 3 being a plan view of a stripper.

The press is of the known type of friction stamping presses and consists of the press frame 1, the spindle 2 and the bar 3. The spindle 2 is held in the bar in the known manner and is driven at its upper end by a friction disc provided with engaging and disengaging device of the known type. The members actuating the engaging and automatic disengaging devices after pressing are also of known construction and for that reason not shown or described here. The attachment of the punch 4 to the bar 3 may also be accomplished in any known and desired manner.

In the press frame 1 to the right and left of the press spindle 2 and between the upper part 1^a and the bed 1^b brake spindles 5 are arranged. The upper and lower ends of the brake spindles 5 bear against balls 6 or other suitable ball bearings. The bar 3 and brake beam 8 move vertically between the side members 1^c of the press on guides 7 formed on said members, and the press spindle 2 slides through an opening formed in the brake beam. The screw threaded portions of the spindles 5 work in threaded bushings 9 which are firmly and immovably arranged in the brake beam 8. The striking rods 10 are also fastened to the brake beam 8 by means of the nuts 11 and pass without friction through the holes 12 in the bar 3. The rods 10 carry on their lower ends the pressure plate 14 which is pro-

vided with stiffening ribs 13. By means of any suitable adjusting device, not shown, the brake beam 8 and the pressure plate 14, which, on account of their own weight, always tend to descend while turning the loose spindles 5, can be fixed in any position. To the bed 1^b of the press frame 1 the matrix 15 is secured in any desired way.

In the present embodiment of the invention the matrix 15 has a somewhat conical circumference and rests in a socket 16 which is also of conical shape. This socket 16 is fitted in the matrix casing 17 and is firmly and immovably kept therein by the threaded ring 18. Rotatably arranged on the matrix casing 17 by means of the screw 20 is the stripper 19 having a form shown in Fig. 3. By means of the screw 21 the stripper 19 is clamped when the press is in pressing position. The diameter of the hole 22 in the stripper 19 is amply dimensioned so as to permit easy guiding of the countersocket 23. On the piece of bronze 24 to be pressed and which is arranged within the matrix 15 rests the stripper ring 25 on which bears the countersocket 23. The internal diameters of the stripper ring 25 and the countersocket 23 are alike and correspond exactly to the external diameter of the punch 4, so that the latter is tightly guided in the countersocket 23 and the stripper ring 25.

The press constructed according to the present invention functions as follows:

After securing the brake beam 8 against movement by means of any suitable adjusting device in its approximately highest position a bronze disc 24 is placed in the matrix 15, the stripper ring 25 placed on top of the bronze plate 24 and the stripper 19 clamped by the screw 21 to the matrix casing 17. The countersocket 23 is then inserted in the hole 22 of the stripper 19 and the securing device of the brake beam 8 released so as to permit the latter to move downward by its own weight while turning the loose spindles 5 until the pressure plate 14 rests on the countersocket 23. Then the press spindle 2 is set in motion, which causes the punch 4 to move through the countersocket 23 towards the bronze plate 24 which is to be pressed. The downward pressure thus applied to the bronze plate 24 causes it to rise at the circumference of the punch 4 and to lift up the countersocket 23, the pressure plate 14 and the brake beam 8 over the stripper ring 25. As the lifting of the brake beam 8 causes the spindles 5 to turn so that a certain amount of power is consumed in turning them, their rotation causes counterpressure to be applied via the brake beam 8 and the pressure plate 14 to the countersocket 23 and also to the rising material of the work piece. This counter-pressure is increased to the extent of the weight of the pressure plate 14, the striking

rods 10 and the brake beam 8. The counter-pressure can be adjusted according to the strength of the material to be pressed and the wall thickness of the hollow body to be formed. This can be very simply done by providing the spindles 5 with threads having a smaller or larger pitch. After pressing the press spindle 2 is rotated in the opposite direction in the known manner and automatically occupies its highest position. During this backward movement the punch 4 tends to take the pressed hollow body with it and thus loosens it in the matrix 15. But as the diameter of the hole 22 of the stripper 19 is smaller than the external diameter of the stripper ring 25 and as the pressed hollow body has been previously loosened in the matrix, the hollow body will be stripped off the punch 4 when the stripper ring 25 strikes the stripper 19. The brake beam 8 is then lifted by means of the adjusting device, the countersocket 23 removed, the stripper 19 turned away from the matrix casing 17 in lateral direction and the pressed hollow body with the stripper ring 25 lifted out of the matrix 15 by means of tongs. By putting in a new bronze plate another hollow body of equal dimensions can then be made.

Although the manufacture of hollow bronze bodies is extraordinarily simplified and cheapened by the method described, it is nevertheless impossible to punch the bronze plate through, i. e., to produce it with a hole passing through it; a very thin bottom remains which, however, can be easily cut out in a simple way after the work piece has been removed from the matrix.

The above described press presses hollow bodies of any shape out of bronze of any metal composition and produces objects that can be used at once after the thin bottom left therein after pressing has been stamped out.

The bronze used for these articles is preferably cast in chill moulds so as to form bars and then cut into plates of suitable height.

I claim:

1. A press for forming hollow objects, comprising a matrix for determining the cross sectional dimension of the object to be formed, a counter-socket arranged within said matrix and adapted to rise against the pressure of the extruded material as the latter rises in the matrix under the pressure of a punch, and brake means exercising a retardative control upon the rise of said counter-socket and imposing a counter-pressure upon the extruding material so as to prevent said material from cracking and at the same time condensing it.

2. A press for forming hollow objects comprising a matrix for determining the cross sectional dimensions of the object to

- be formed, a counter-socket arranged within said matrix and adapted to rise against the pressure of a punch, and a screw spindle 5
brake operatively associated with said counter-socket exercising a retardative control over the rise of said counter-socket for imposing a counter-pressure upon the extruding material so as to prevent it from cracking and at the same time condensing it.
- 10 3. A press for forming hollow objects, comprising a matrix for determining the cross sectional dimensions of the object to be formed, a counter-socket arranged within said matrix and adapted to rise against the pressure of the extruded material as the latter rises in said matrix under the pres-
- sure of a punch, a brake beam, a pressure plate associated with said brake beam and adapted to bear against said counter-socket, and screw spindles threaded into said brake beam and rotating in response to the reciprocatory movement thereof to apply counter-pressure through said brake beam and pressure plate to said socket, thereby exercising a retardative control over the rise of 20
25 said counter-socket and imparting a counter-pressure upon the extruding material so as to prevent it from cracking and at the same time condensing it.

In testimony whereof I affix my signature.

ALWIN SCHMITZ.
